UNITED STATES PATENT OFFICE.

HUBERT M. GRAY, OF TOLEDO, OHIO.

LUBRICATING DEVICE FOR LOCOMOTIVE-JOURNAL BOXES.

Application filed January 20, 1926. Serial No. 82,393.

This invention relates to locomotive drive boxes but particularly to a lubricating device for locomotive journal boxes and associated parts.

Objects of this invention are to provide a new and improved lubricating device for wedges ordinarily used in connection with journal boxes for locomotives and the like which may be automatic, efficient and reliable in operation, to provide means controlled by rotation of the axle for effecting lubrication between a locomotive journal box and the usual reversely positioned wedges associated therewith whereby lubricant is automatically delivered to the various parts and is retained in sufficient quantities so that in the event that the main supply is checked or shut off, the tube surfaces will be lubricated, thereby eliminating the danger of hot boxes; and to provide a reliable and efficient device of the above character having the new and improved features of construction and arrangement herein-after more clearly described.

This invention comprises in one of its aspects a lubricating device for locomotive drive boxes having ports, passages and channels so arranged that lubricant is forced by the rotating axle to the various parts so that efficient lubrication is secured. Such device is intended particularly for use in connection with oppositely positioned wedges which are customarily used in drive boxes and has been found admirably adapted for maintaining well lubricated surfaces over an extended period of time, even though the main supply should give out. It may be here said that this is accomplished by the provision of channels or relatively shallow grooves which are adapted to retain lubricant until such time as it is needed.

This invention is shown for purposes of illustration in the accompanying drawings, in which,

Fig. 1 is a side view of a locomotive drive box assembly; Fig. 2 is a transverse section on the line 2—2 of Fig. 1; Fig. 3 is a side elevation of one of the wedges; Fig. 4 is a side elevation of the other wedge; Fig. 5 is a front elevation of the drive box; Fig. 6 is an end view of the drive box; and Fig. 7 is a bottom plan view of the drive box.

The illustrated embodiment of the invention comprises a locomotive drive box housing 1 of usual construction having an opening 2 to receive the locomotive drive box

3 which is formed with flanges 4 at each side thereof to fit over the sides of the housing 1 as indicated in Fig. 2. Secured to the upper portion of the drive box 3 is a crown brass 5 which is formed with a portion extending outwardly from the drive box after a manner well known in the art.

Rotatable within the drive box is the axle 6 and positioned beneath the axle and in engagement therewith is a screen 7 against which lubricating material 8, such as saturated felt-like material, hard oil or other suitable lubricant is pressed by a coil spring 9 acting against a follower plate 10. The lubricating device is arranged within a cellar or casing 11 which is suitably supported in the drive box 3. It will thus be seen that rotation of the axle 6 draws lubricant from the material 8, and, as the material becomes used the spring 9 compensates therefor, thereby maintaining a constant pressure and supply of lubricant to the axle. To remove the lubricant-casing 11, a pin 13 detachably engaging ears in the casing 11 and drive box 3 respectively, may be removed so that the casing may drop out or be removed for replenishing the lubricant supply.

In order to hold the drive box 3 in position, a bar 12 extends horizontally beneath the housing 1 and is attached thereto in any suitable or desired manner. For eliminating lateral play or motion between the drive box 3 and housing 1 oppositely positioned wedges 14 and 15 are arranged within the housing 1, one side of the wedge 14 engaging the housing and one side of the wedge 15 engaging the drive box 3. When the wedges 14 and 15 are properly positioned undesirable relative movement between the drive box 3 and housing is eliminated, although sufficient movement is permitted to prevent excessive wear between the parts and also to enable the vehicle to ride more easily without the attending jars and shocks which otherwise would be occasioned. In view of the fact that the use of these wedges is old in the art further description and discussion thereof is deemed unnecessary.

Spring means are provided for holding the wedge 14 in properly adjusted position, and, for this purpose a screw is in threaded engagement with the bar 12 and extends into the wedge 14. A collar 17 is mounted on the screw and a coil spring 18 between the collar 17 and bracket 19 urges the wedge 14 yieldingly upward. It is to be understood,

however, that the above adjustment feature is well known and forms no part of the present invention.

In accordance with the present invention, means are provided for lubricating the surfaces between the wedges 14 and 15, and also between the wedges and respective adjacent surfaces so that in operation the parts may move relative to each other and the binding which has heretofore frequently occurred between the parts is eliminated. Furthermore, means are provided for retaining sufficient amount of lubricant in the region of the relatively moving surfaces so that should the main supply become exhausted the stored lubricant will then be brought into use so that the liability of hot boxes and crystallization is materially reduced. A further feature of the invention resides in that lubricant is automatically distributed by means of the axle to the desired parts and this has been found to be much more advantageous than a manual force feeding which has heretofore been employed because of the more reliability of operation of the axle distributing medium. Owing to the tremendous pressure which is imposed upon locomotive driving boxes the feeding of lubricant manually to more or less secluded parts has been found decidedly impractical.

Referring to the drawings, the wedge or shoe 15 is formed with a plurality of longitudinally spaced ports 20 which extend through the wedge from one side to the other, and it will be understood that the number and arrangement of these ports or apertures may be changed in any desired manner which is found in practice to be of most advantage. Communicating with the ports 20 are passages 21 on each side of the wedge and these passages are inclined in different directions and terminate at points spaced inwardly from the side edges of the wedge.

The wedge 14 is similarly formed with ports 22 extending transversely from one side to the other and communicating with the ports 22 are zigzag channels 23 on each side of the wedge. The ports and channels in this wedge may likewise be arranged in any suitable or preferred manner, although it has been found that the arrangement shown on the drawings is admirably adapted for the purpose.

As most clearly indicated in Figs. 5 and 6, the outer side of the drive box 3 adjacent the wedge 15 is formed with a series of communicating channels 24 arranged in the form of a parallelogram with channels connecting various sides of the parallelogram. Communicating with this channel arrangement is a passage 25 which extends through the drive box and crown brass 5. The inside of the crown brass 5 is provided with an X-shaped channel 26 and communicating there-

with is a channel 27 which leads from the passage 25. The opposite end of the channel 27 communicates with a passage 28 which leads through the drive box to a shoe 29, which is arranged between the drive box and the drive box housing. A channel 30 leads from the X-channel 26 and communicates with a passage 31 which terminates at the front face of the drive box 3.

In operation, a portion of the lubricant from the lubricating material 8 is carried by the axle 6 to the X-channel 26 and other channels in the crown brass 5 and some of this lubricant is forced through the channel 27 and passage 25 to the series of channels 24. Some of the lubricant from the channels 24 passes into the channels 21 in the wedge 15 and through the ports 20 to the opposite side thereof. The lubricant then finds its way into channels 24 in the wedge 14 and on both sides thereof.

It will be seen that by this arrangement lubricant is thoroughly distributed over the rubbing surfaces of the wedges, drive box and driving box housing. It is to be noted that a small amount of lubricant will constantly be passed through the above mentioned channels, passages and ports and the over abundant supply will be retained in the channels or at least some of them so that, in the event that the main supply of lubricant becomes exhausted or that some of the passages become clogged or for some other reason the main feed is closed, the lubricant stored in the channels can then be utilized to prevent the creation of hot boxes and other disastrous results usually resultant from lack of lubricant. In this manner the channels provide a reserve supply of lubricant when needed.

Lubricant is likewise forced through the channel 27, and passage 28 to the shoe 29 so that the surface between this shoe and driving box housing is lubricated. Furthermore, lubricant is passed through the channel 30, passage 31 to the front face of the drive box so that the ring which ordinarily surrounds the outer end of the crown brass receives adequate lubrication.

While I have shown and described a construction which is the best form known to me at the present time, it is to be understood that numerous changes in details of construction and arrangement may be effected without departing from the spirit of the invention, especially as defined in the appended claims.

What I claim as new and desire to secure by Letters Patent, is:

1. A device of the class described comprising a housing, a journal box in the housing, an axle in said journal box, a pair of reversely positioned wedges between the outside of said journal box and said housing, lubricating ports extending through each

wedge, lubricating channels or grooves in the faces of said wedges, a passage leading from the inside of said box to the adjacent wedge, and means for supplying lubricant to said axle whereby the axle carries a portion of the lubricant to the journal box passage from which it passes to the passages and channels in the wedges, and the wedge channels retain sufficient lubricant to take care of lubrication between the wedges and adjacent surfaces, in the event the main supply becomes exhausted or stopped up.

2. A device of the class described comprising a housing, a journal box in the housing, a crown brass for said journal box, an axle in said journal box, a pair of reversely positioned wedges between the outside of said journal box and said housing, lubricating ports extending through said wedges, lubricating channels formed in the faces of

said wedges, a passage leading from the inside of said journal box to the adjacent wedge, a passage from the inside of said crown brass to the outer face thereof, and means for supplying lubricant to said axle whereby the axle carries a portion of the lubricant to the journal box passage from which it passes to the passages and channels in the wedges, and the wedge channels retain sufficient lubrication to take care of lubrication between the wedges and adjacent surfaces in the event the main supply becomes exhausted or stopped up, and lubricant is also carried through the passage in said crown brass for lubricating the outer face thereof.

In testimony whereof I have hereunto signed my name to this specification.

HUBERT M. GRAY.
